UNITED STATES PATENT OFFICE.

ELMER R. CORWIN, OF CHICAGO, ILLINOIS, ASSIGNOR TO CORWIN TELEPHONE MANUFACTURING COMPANY, OF CHICAGO, ILLINOIS.

TELEPHONE SYSTEM.

1,071,208.

Specification of Letters Patent. Patented Aug. 26, 1913.

Application filed October 12, 1908, Serial No. 457,197. Renewed July 18, 1911. Serial No. 639,203.

To all whom it may concern:

Be it known that I, ELMER R. CORWIN, citizen of the United States, residing at Chicago, in the county of Cook and State of Illinois, have invented a certain new and useful Improvement in Telephone Systems, of which the following is a full, clear, concise, and exact description, reference being had to the accompanying drawings, forming 10 a part of this specification.

My invention relates to telephone exchange systems, some features thereof being of particular service in connection with multiple switch-board systems to which, however, the invention is not to be restricted.

The invention in its various aspects, is well exhibited by the accompanying drawing, showing one of the embodiments of the invention as applied to a multiple switch-board system, there being illustrated two telephone sub-stations A B at each of which there is shown a telephone switch-hook *a* adapted to support a receiver *b* which serves to include said switch-hook in circuit with a signal bell *c*, and a condenser *e*, that are included by the switch-hook in a bridge of the associate telephone line. When the receiver is free of the switch-hook, said switch-hook opens the bridge containing the signal bell *c* and condenser *e* and includes the receiver *b* and transmitter *f* in circuit and places the retardation coil *f¹* in parallel with a receiver *b* for the purpose of supplying the transmitter *f* with current from the common battery *f²*. The limbs *g* and *h* of each telephone line are shown in this instance as terminating in the armature switches of the associate cut-off relay *i*, the normal contact of the uppermost armature switch constituting the terminal of a conductor that contains a line relay *i¹* and the common battery *i²*, while the normal contact of the lowermost armature switch of the relay *i* is grounded. When a call is sent to the exchange by the calling subscriber in removing his switch-hook, the magnet *i¹* is included in the circuit that includes the battery *i²* and the limbs *g* and *h* of the telephone line, as will be apparent by an inspection of the drawing.

Upon the closure of the circuit through the magnet *i¹*, a circuit is established through the line signal-display device *i³*, preferably in the form of a small incandescent lamp, which circuit includes the battery *i²* and front contact of the magnet *i¹*. The

front or alternate contacts of the armature switches of the cut-off relay *i* constitute the normally separated terminals of sections of the line limbs *g* and *h* that extend to the multiple jacks *k*. When an operator answers a call by inserting the answering plug *l* within an answering jack, a circuit is established through the cut-off relay *i* which may be traced from the grounded terminal of said cut-off relay, through the winding of the relay, the thimble of the jack *k* engaged by the plug *l*, the sleeve of the jack, the relay *m*, the battery *f²*, to the grounded terminal of said battery. The cut-off relay *i* and the relay *m* are thus included in a local circuit that serves to energize said cut-off relay and maintain the spring-jack extensions of the telephone line in connection with the armature switches of said cut-off relay until the circuit of said cut-off relay is broken by the withdrawal of the plug *l* from the associate spring jack. The system illustrated being a two-wire metallic circuit system, one of the talking strands of the cord circuit (in this instance the talking sleeve strand of the cord circuit) is employed to take part in establishing the local circuit for the cut-off relay *i*, with the results that have been stated. When the cut-off relay has been energized the line relay *i¹* is excluded from circuit, and, being deenergized, excludes the line signal-display device *i³* from circuit. The receiver *b* at the calling station being off of its hook, the bridge between the talking strands of the cord circuit which includes the relay *m*, the battery *f²* and another relay *n*, is closed, so that the relay *n* is energized at the same time with relay *m*, whereby circuit through the calling subscriber's supervisory or clearing-out signal *n¹* is opened at relay *n*.

When the calling subscriber is through, he restores his receiver, thereby opening the circuit of the relay *n*, the signal device *n¹* then being included in circuit owing to the continued energization of the relay *m*, whereby the operator will know that the calling subscriber has restored his receiver. When the operator removes the answering plug, the signal device *n* is restored to normal owing to the breakage of the local circuit including the relay *m*. After the operator has plugged into the answering jack of a calling subscriber, a circuit is established which may be traced from the grounded relay *o* to the normal contact of the lower-

most armature switch of relay p , said armature switch, to the right-hand armature switch of relay m , to the grounded battery f^2 . The relay o thus being included in circuit, attracts its armature switches, whereby the operator's set q is included in circuit and the operator's transmitter is supplied with current from the common battery f^2 . The operator then listening to the wants of the calling subscriber, tests the line of the subscriber with whom the calling subscriber desires connection, by applying the tip of the connecting plug r to the test thimble of a line jack of the desired subscriber's line, and if the line is busy, a test circuit is established which may be traced from the grounded battery f^2 to the sleeve of some plug engaging some jack of the desired subscriber's line, thence to the thimble tested, the tip of the testing plug, the back contact of the uppermost armature switch of the relay p , through one-half of the winding of the operator's receiver q , to the grounded buzzer g^1 , whose armature serves by its vibration to open and close the circuit of said buzzer g^1 , said buzzer being in serial relation with a receiver winding of the operator's receiver and the balance of the instrumentalities that are included in the test circuit. If the line desired is idle, there will be no battery f^2 upon any of the thimbles of its jacks, in which event the relay g^1 will not be included in any operating circuit, so that the operator will know that the line desired is idle and may be called. The operator inserts the connecting plug r in a line jack of a desired line that may be called, whereupon a number of changes in the operated conditions of the plug circuit apparatus occur, which I will now describe.

The relay p is included by the connecting plug in a local circuit which may be traced from the grounded battery p^1 through the winding of the relay p , a portion of the sleeve strand of the connecting plug r , the thimble of an engaged jack, to the cut-off relay i of the called subscriber's line, said cut-off relay preventing the called subscriber from operating his line signal when he responds. The armature switches of the relay p are thereupon attracted, the lowermost armature switch serving to open the circuit including the relay o , whereby the operator's telephone outfit is excluded from connection with the plug circuit and the talking battery f^2 is removed from connection with the operator's transmitter. Ringing current is then applied to the called subscriber's line, but before describing the manner in which the ringing or signaling current is thus applied, I will describe the supervisory apparatus that is controlled by the called subscriber.

The supervisory apparatus includes a relay s contained in a grounded tap from the

tip strand of the cord circuit, the circuit for said supervisory relay s , including, when the called subscriber has responded, a portion of the tip strand of the plug circuit, the tip side of the called subscriber's line, the sleeve side of the called subscriber's line, a portion of the sleeve strand, and the battery p^1 . When the supervisory relay circuit s is closed, the supervisory display device s^1 is excluded from circuit, but until the called subscriber responds, the supervisory relay circuit s is not open, whereby the operator, by observing the signal s^1 , is aware that the called subscriber has not responded, said signal device s^1 being included in a circuit which may be traced from the grounded terminal of the lamp s^1 to the left-hand armature switch of the relay s , to the battery p^1 . The relay p having, as has been stated, been energized upon the insertion of the connecting plug within the line jack of a called subscriber, places the normally isolated sections t, t of the talking strands of the plug circuit in connection with the uppermost armature switches of the relay p , whereby said talking strand sections are connected with the called line. These talking strand sections are normally connected with the terminals of a source of signaling current u by the upper armature switches of the relay v when in their normal unattracted position, whereby said source of signaling current u is included in circuit with a called subscriber's line.

In order that the signaling current may be intermittently applied to the called line, brushes u^1 are employed which bear upon collars u^2 that are made of alternating strips of conducting and non-conducting material. During the time that current is being impressed upon the called subscriber's line, the signal w is intermittently operated by being included in serial relation with the normal contacts of the lowermost armature switch of the relay v , said circuit also including two brushes resting upon a collar x composed of alternating strips of insulating and conducting material, whereby a characteristic signal is conveyed by the signal device w . The circuit for said device w may be traced from the grounded brush bearing upon the collar x to the companion brush, the signal device w , the normal contacts of the lowermost armature switch of the relay v , the lowermost armature switch of relay p , to the grounded battery p^1 .

The collars u^2 are driven by a motor y in circuit with the battery p^1 , said motor effecting an intermittent inclusion of the generator in circuit and corresponding intermittent operation of the ringing signal w . When the called subscriber responds, circuit through the magnet v is closed, thereby excluding the signal w and connecting the normally isolated sections t, t of the

cord circuit with the answering end of the cord circuit and, consequently, removing the calling generator from circuit. It will be observed that the signal u is individual to its cord and is not common to the signaling generator. I have shown but one cord circuit, but it is understood that there are other cord circuits similar in equipment to the cord circuit shown. The energizing circuit for the relay v may be traced from the grounded brush bearing upon the collar z , formed of alternating sections of insulating and conducting material, the companion brush, when united with the grounded brush by means of a conducting section of said collar, the upper coil of the relay v , the still unattracted right-hand armature switch of the supervisory relay s (the relay s not being adapted to be energized until after the relay v has been energized, as will be apparent by an inspection of the diagram), the called subscriber's portion of the tip strand of the cord or plug circuit, the tip line spring of the engaged jack, the limbs of the called subscriber's line and the receiver bridge of the called subscriber's station, the thimble of the jack engaged by the connecting plug, to the grounded battery p^1 . A locking circuit is established for the relay v when it is energized, which locking circuit may be traced from the grounded terminal of the lower coil of said relay, the attracted lowermost armature switch of said relay, the attracted lowermost armature switch of relay p , to the grounded battery p^1 , this locking circuit serving to prevent the re-inclusion of the signaling generator u in circuit with the called line. The locking circuit is broken in order that the normal connection of the isolated sections t of the cord circuit may again be established with the generator u , the opening of said locking circuit occurring when the relay p is deenergized, which deenergization occurs upon the break in the circuit of the relay p occurring at the thimble of the engaged jack and the sleeve of the inserted plug when said plug is separated from said jack.

It will be observed that the brushes bearing upon the collar z are never in circuit with the brushes bearing upon the collar z and that the brushes upon the collar z are never in circuit with the brushes upon the collar u^2 , in order that current from the ringing generator u may not find passage through the energizing coil of the relay v . Cross reference may be had to my co-pending application, Serial No. 457,196, filed October 12, 1908 and in which some features that are herein disclosed are therein disclosed.

I have thus described the preferred embodiment of my invention, but I do not wish to be limited to the adaptation of the invention herein set forth, nor to the precise de-

tails of construction shown, as changes may be made without departing from the spirit of the invention.

Having thus described my invention, I claim as new and desire to secure by Letters Patent:—

1. A telephone exchange system including telephone lines extending from sub-stations to an exchange, link circuits at the exchange for constituting continuations of calling telephone lines, an operator's telephone set, a relay for including said telephone set in telephonic connection with the calling line, a circuit for said relay governed without the control of the substations and by the answering end of the link circuit, to energize said relay and thereby include the operator's telephone set in circuit, and relay mechanism included in a local circuit that contains contacts provided upon the connecting plug and engaged with a line jack for deenergizing the aforesaid relay, thereby to cut the operator's telephone set out of circuit.

2. A telephone exchange system including telephone lines extending from sub-stations to an exchange, link circuits at the exchange for constituting continuations of calling telephone lines, an operator's telephone set, a relay for including said telephone set in telephonic connection with the calling line, a circuit for said relay established without the control of the substations and upon connecting the answering end of the link circuit with a calling line, to energize said relay and thereby include the operator's telephone set in circuit, and relay mechanism included in a local circuit that contains contacts provided upon the connecting plug and engaged with a line jack for deenergizing the aforesaid relay, thereby to cut the operator's telephone set out of circuit.

3. A telephone exchange system including telephone lines extending from sub-stations to an exchange, link circuits at the exchange for constituting continuations of calling telephone lines, an operator's telephone set, a local circuit relay for including said telephone set in telephonic connection with the calling line, a circuit for said relay without the control of the sub-stations and governed by the answering end of the link circuit, to energize said relay and thereby include the operator's telephone set in circuit, and relay mechanism governed by the connecting end of the link circuit for deenergizing the aforesaid relay, thereby to cut the operator's telephone set out of circuit.

4. A telephone exchange system including telephone lines extending from sub-stations to an exchange, link circuits at the exchange for constituting continuations of calling telephone lines, an operator's telephone set, a local circuit relay for including said telephone set in telephonic connection with the

calling line, a circuit for said relay without the control of the sub-stations and established upon connecting the answering end of the link circuit with a calling line, to 5 energize said relay and thereby include the operator's telephone set in circuit, and relay mechanism governed by the connecting end of the link circuit for deenergizing the aforesaid relay, thereby to cut the operator's 10 telephone set out of circuit.

5. A telephone exchange system including telephone lines extending from sub-stations to an exchange, link circuits at the exchange for constituting continuations of calling 15 telephone lines, an operator's telephone set, a local circuit relay for including said telephone set in telephonic connection with the calling line, a circuit for said relay without the control of the sub-stations and governed 20 by the answering end of the link circuit, to energize said relay and thereby include the operator's telephone set in circuit, and relay mechanism governed by the connecting end of the link circuit and the jack of the called 25 line, for deenergizing the aforesaid relay, thereby to cut the operator's telephone set out of circuit.

6. A telephone exchange system including telephone lines extending from sub-stations to an exchange, link circuits at the exchange for constituting continuations of calling telephone lines, an operator's telephone set, a local circuit relay for including said telephone set in telephonic connection with the calling line, a circuit for said relay without the control of the sub-stations and established upon connecting the answering end of the link circuit with a calling line, to energize said relay and thereby include the operator's telephone set in circuit, and relay mechanism governed by the connecting end of the link circuit and the jack of a called line, for deenergizing the aforesaid relay, thereby to cut the operator's telephone set out of circuit.

7. A telephone exchange system including telephone lines extending from sub-stations to an exchange, link circuits at the exchange for constituting continuations of calling 50 telephone lines, an operator's telephone set, a local circuit relay for including said telephone set in telephonic connection with the calling line, a circuit for said relay governed without the control of the sub-stations and 55 by the answering end of the link circuit, to energize said relay and thereby include the operator's telephone set in circuit, and relay mechanism included in a local circuit that contains contacts provided upon the connecting 60 plug and engaged with a line jack for deenergizing the aforesaid relay, thereby to cut the operator's telephone set out of circuit.

8. A telephone exchange system including
65 telephone lines extending from sub-stations

to an exchange, link circuits at the exchange for constituting continuations of calling telephone lines, an operator's telephone set, a local circuit relay for including said telephone set in telephonic connection with the calling line, a circuit for said relay established without the control of the sub-stations and upon connecting the answering end of the link circuit with a calling line, to energize said relay and thereby include the operator's telephone set in circuit, and relay mechanism included in a local circuit that contains contacts provided upon the connecting plug and engaged with a line jack for deenergizing the aforesaid relay, thereby to cut the operator's telephone set out of circuit.

9. A telephone switch-board system including telephone lines extending from substations to an exchange, link circuits for uniting lines in conversation, a source of signaling current, means for connecting the same with a called line, a signaling circuit containing a responsive device, individual to the link circuits, supplied in addition to the supervisory or disconnect signals and performing their functions independently thereof, said responsive devices being independently operable, and means for impressing upon said circuit a characteristic signaling current during the connection of the source of signaling current with the called telephone line. 85 90 95

10. A telephone switch-board system including telephone lines extending from substations to an exchange, link circuits for uniting lines in conversation, a source of signaling current, means for connecting the same with a called line, a local signaling circuit containing a responsive device individual to the link circuits, supplied in addition to the supervisory or disconnect signals and performing their functions independently thereof, said responsive devices being independently operable, and means for impressing upon said circuit a characteristic signaling current during the connection of the source of signaling current with the called telephone line. 100 105 110

11. A telephone switch-board system including telephone lines extending from substations to an exchange, link circuits for uniting lines in conversation, a source of signalling current, means for connecting the same with a called line a signalling circuit containing a responsive device individual to the link circuits, supplied in addition to the supervisory or disconnect signals and performing their functions independently thereof, said responsive devices being independently operable, means for impressing upon said circuit a characteristic signalling current during the connection of the source of signalling current with the called telephone line, and mechanism under the control of the 120 125 130

called subscriber for excluding the source of signaling current from circuit with the called subscriber's line.

12. A telephone switch-board system including telephone lines extending from sub-stations to an exchange, link circuits for uniting lines in conversation, a source of signaling current, means for connecting the same with a called line, a local signaling circuit containing a responsive device individual to the link circuits, supplied in addition to the supervisory or disconnect signals and performing their functions independently thereof, said responsive devices being independently operable, means for impressing upon said circuit a characteristic signaling current during the connection of the source of signaling current with the called telephone line, and mechanism under the control of the called subscriber for excluding the source of signaling current from circuit with the called subscriber's line.

13. A telephone exchange system including telephone lines extending from sub-stations to an exchange, link circuits at the exchange for constituting continuations of calling telephone lines, an operator's telephone set, a relay for including said telephone set in telephonic connection with the calling line, a circuit for said relay without the control of the sub-stations and governed by either end of the link circuit, to energize said relay and thereby include the operator's telephone set in circuit, and means governed by either end of the link circuit companion to the end of the link circuit that enters into the government of said relay, for effecting the deenergization of said electro-magnet or relay, thereby to cut the operator's telephone set out of circuit.

14. A telephone exchange system including telephone lines extending from sub-stations to an exchange, cord circuits, each provided with terminal plugs adapted for connection with telephone lines to unite the same in conversation, an operator's telephone outfit adapted for telephonic connection with the telephone lines, switching mechanism governing the association of the operator's telephone outfit with the telephone lines, an electro-magnet governing the

operation of said switching mechanism, a source of current for energizing said electro-magnet, switching devices governed by the plugs of each cord circuit, and circuit connections governed by said plugs and switching devices, whereby when a plug and one of said switching devices co-act, current is caused to flow through said electro-magnet to cause it to operate the switching mechanism, and when both plugs co-operate with both switching devices, current is diverted from said electro-magnet to cause it to release the switching mechanism that it controls, thereby to remove the operator's telephone set from circuit relation with united telephone lines.

15. A telephone exchange system including telephone lines extending from sub-stations to an exchange, cord circuits, each provided with terminal plugs adapted for connection with telephone lines to unite the same in conversation, said telephone lines having jack switches for the reception of the plugs, an operator's telephone outfit adapted for telephonic connection with the telephone lines, switching mechanism governing the association of the operator's telephone outfit with the telephone lines, an electro-magnet governing the operation of said switching mechanism, a source of current for energizing said electro-magnet, and circuit connections leading to said jack switches and said plugs, whereby when a plug and one of said jack switches co-act, current is caused to flow through said electro-magnet to cause it to operate the switching mechanism, and when both plugs co-operate with both jack switches, current is diverted from said electro-magnet to cause it to release the switching mechanism that it controls, thereby to remove the operator's telephone set from circuit relation with united telephone lines.

In witness whereof, I hereunto subscribe my name this 10th day of October A. D. 1908.

ELMER R. CORWIN.
